H. C. SPENCER.
GARMENT PRESSING MACHINE.
APPLICATION FILED MAR. 25, 1920.

Patented Oct. 19, 1920.

Fig. 1.

UNITED STATES PATENT OFFICE.

HAROLD CORTLAND SPENCER, OF SYRACUSE, NEW YORK.

GARMENT-PRESSING MACHINE.

1,356,321.

Specification of Letters Patent. Patented Oct. 19, 1920.

Application filed March 25, 1920. Serial No. 368,680.

To all whom it may concern:

Be it known that I, HAROLD C. SPENCER, of Syracuse, in the county of Onondaga, in the State of New York, have invented new and useful Improvements in Garment-Pressing Machines, of which the following, taken in connection with the accompanying drawings, is a full, clear, and exact description.

This invention relates to certain improvements in garment pressing machines involving the use of similar coöperative pressing elements, movable one in relation to the other, in which steam is applied to the garment for moistening purposes through perforations or apertures in the press plates of one or the other of said elements.

In machines of this character now in common and extensive use, provision is made for holding the pressing elements against relative movement during the pressing operation, as distinguished from ironing machines, to avoid imparting an objectionable glossy or shiny appearance to the garment, and, for the same purpose, the meeting faces or press plates of both elements are usually covered with cloth or fabric pads of varying thicknesses, which also perform the function of distributing the steam moisture more evenly over the surface or surfaces of the garment under pressure.

Furthermore, these pressing elements are usually steam heated and provided with perforations in one or the other of the press plates for the admission of steam to the pads and thence to the garment for moistening purposes.

The main object of my present invention is to utilize a machine of this character for ironing purposes, or for the purpose of imparting more or less gloss to certain kinds of garments, such, for example, as duck, linen and similar coats, vests, trousers, skirts and the like, without leaving the imprints of the steaming perforations or the steam jets upon the garment.

In carrying out this object, the pads or fabric coverings for the press plates are omitted, and the press plates are made of metal having their surfaces polished so as to move freely across the surface of the garment while the latter is under pressure, one or the other of said plates being perforated or provided with apertures through which the steam may be projected to the garment for moistening purposes.

It, therefore, follows that if, under these conditions, the pressing elements were allowed to remain in fixed relative positions during the pressing operation, the steam applied to the garment through said perforations would leave objectionable imprints of the steam jets upon the surface of the garment, and one of the specific objects of my invention is to take advantage of this highly desirable method of applying steam to the garment for moistening purposes, and, at the same time, to impart to the garment the desired gloss without leaving the imprints of the steam jets upon the surface thereof.

In other words, I have sought to provide in a machine of this character, in which one or the other of two similar pressing elements is provided with a perforated or apertured press plate, means for projecting steam through the perforations of the garment, and additional means for causing the press plate of one of the pressing elements to traverse the surface of the opposite press plate under a slight reciprocatory or recurrent motion while the pressing elements are in their pressing positions in contact with the garment for imparting a glossy finish to the surface or surfaces of said garment during or following the application of steam thereto through the perforated or apertured plate, whereby the reciprocatory or recurrent movement will obliterate any impressions or imprints of the steam jets upon the garment.

Other objects and uses relating to specific parts of the machine will be brought out in the following description:

In the drawings:

Figure —1— is a top plan, partly in section, of a portion of a garment pressing machine embodying the various features of my invention.

Fig. —2— is an end view, partly in section, of the same machine, an electric motor being shown by dotted lines as the source of power for driving the mechanism which produces a reciprocatory re-current motion of one of the pressing elements.

Fig. —3— is a side elevation of a portion of the supporting frame for the upper pressing element, showing the means whereby said frame may be reciprocated horizontally and rocked vertically upon its supporting shaft.

Fig. —4— is a detailed sectional view of the lower pressing element, and means for reciprocating the same horizontally.

Fig. —5— is a sectional view taken in the 5 plane of line 5—5, Fig. —4—.

In order that my invention may be clearly understood, I have shown a pair of similar coöperative pressing elements, which may be, respectively, termed a buck —1— and 10 press head —2—, the buck —1— mounted in a horizontal position upon a suitable support —3— which may be a part of the main supporting frame, while the press head —2— is mounted upon the front end 15 of a rock-arm or frame —4— having its intermediate portion suitably supported to permit the frame to be rocked vertically about the axis of a horizontal shaft —5— some distance to the rear of and approxi- 20 mately in the same horizontal plane as the meeting faces of the pressing elements —1— and —2— when the latter are in their pressing positions, the axis of the shaft —5— being substantially parallel with the 25 longitudinal centers of said pressing elements, the end of said frame —4— being adapted to receive a counter weight or spring, not shown, for automatically raising the head —2— following the pressing 30 operation.

The buck —1— is provided with a heating chamber —6— adapted to be connected by a pipe —7— to any available source of steam supply for keeping the buck at the 35 desired temperature for sterilizing and drying purposes without liability of overheating the garment.

As illustrated, in Figs. —2—, —4— and —5—, the buck —1— is slidably mounted 40 upon its support —3—, and for this purpose, said support is provided at its upper end with an annular flange —8—, upon which the bottom of the main body of the buck rests. A retaining plate —9— is se- 45 cured by bolts —10— to the underside of the main body of the buck —1— around the flange —8— and is engaged with the under- side of said flange to hold the buck in a horizontal position against displacement 50 from its support —3—, leaving sufficient clearance between the sides of said support and the side walls of the plate —9— to allow the buck to be reciprocated horizontally upon the support —3—.

55 The means for producing this reciprocatory or recurrent motion consists, in this instance, of a revoluble vertical shaft journaled in a central opening —12— in the support —3—, and having its upper end provided with an eccentric —13— which 60 enters a recess —14— in the underside of the main body of the buck and engages a bearing block —15— in said recess, said recess and bearing block being preferably an- 65 gular in cross-section to prevent rotation of

the block by the rotation of the eccentric —13—, and, at the same time, serving as a means of transmitting motion from said eccentric to the buck relative to the head —2—.

70 The shaft —11— may be driven by any suitable mechanism, but will preferably be driven by suitable connections with an electric motor —A—, these connections not being shown for the reason that anyone skilled in the art would readily provide suitable mechanism for transmitting motion from the motor shaft to the shaft —11—.

75 The head —2— is provided with a heating chamber —17— and a distributing chamber —16— disposed one above the other and separated by a partition —18— to form non-communicating compartments, both of which are connected by branches 80 —19— and —20— to a supply pipe —21— leading from any available source of steam supply, not shown. The branch pipe —20— leading to the steam compartment or distributing chamber —16— is provided 85 with a self-closing valve —22— having a hand lever —23— by which it may be opened at will to allow steam to pass to the chamber —16—. Both of the pressing elements are provided with substantially 90 flat press plates —24— and —25— of suitable metal, having their adjacent faces polished and exposed, one to the other for engaging the adjacent surfaces of a garment which may be placed between them 95 for moistening and pressing purposes, the press plate —25— of the head —2— being provided with perforations or openings —26— to permit the steam to pass from the chamber —16— to the garment for 100 moistening said garment when the pressing elements are brought together.

105 A baffle plate —27— is supported in the chamber —16— parallel with and spaced apart from the press plate —25— and partition —18— to cause the distribution of the steam laterally around the edges of the baffle plate, which edges are spaced apart from the side walls of the chamber —16— to allow the steam to pass through the perforations —26—.

110 Suitable means are also provided for causing a reciprocatory or recurrent horizontal movement of the press plate —25— while the head —2— is in its pressing position for 115 obliterating the imprints of the steam jet upon the garment, and also for producing the desired gloss or finish to the adjacent surface of the garment which is preferably placed upon the press plate —24— with the 120 surface to be finished uppermost.

125 The means for producing this reciprocatory or recurrent motion of the head —2— preferably consists of a rotary eccentric —28— which is secured to the shaft —11— 130

within a recess or opening —29— in the frame —4— and is preferably engaged with a wearing block or bearing —30—.

The recess —29— is elongated vertically to correspond with the throw of the eccentric —28—, the bearing block —30— being slideable vertically in said recess by the rotation of the eccentric, and engages the side walls of the recess to impart backward and forward movement of the frame —4—, and to thereby cause the plate —25— to traverse the surface of the garment resting upon the plate —24— while the press head is in its pressing position and during the following application of steam to the garment through the perforations —26—, thereby preventing the formation of the steam jet impressions or imprints upon the surface of the garment, and, at the same time, imparting thereto the desired gloss or finish, it being understood that a similar effect takes place by the horizontal gyratory or recurrent motion of the buck —1— by the rotation of the eccentric —13—.

The shaft —5— is journaled in stationary bearings —31— on the main supporting frame, as —B—, and is held against radial movement by said bearings, and is also held against axial movement by collars —32—, which engage the outer ends of the bearings. The bearing block —30— is held against endwise movement in the recess —29— by plates —33— which are secured by bolts —34— to the opposite sides of the adjacent portion of the frame —4—, and are provided with forwardly and rearwardly elongated slots —35— for receiving the adjacent portion of the shaft —5—, and permitting forward and rearward movement of the said frame and head —2—, as the eccentric —28— is rotated, the plates —33— being engaged with the inner ends of the bearings —31— to hold the frame against axial movement along the shaft —5—.

The motor A may be secured in any suitable manner to the frame B, and its armature shaft provided with a worm —36— meshing with the worm gear —37— on the shaft —5— for rotating the cam or eccentric —28—, and thereby imparting horizontal reciprocating motion to the head —2— through the medium of its supporting frame —4—.

Any well known form of pedal operated mechanism, not shown, may be used for rocking the frame —4— about the axis of its supporting shaft —5—, or it may be moved upwardly and downwardly by means of a handle —38— on the front portion of the head —2—, as shown in Figs. —1— and —2—.

Operation.

The garment to be treated is placed upon the upper surface of the buck —1—, pref-

erably, the head —2— is raised or rocked upwardly and rearwardly, which leaves a clear open space at the front for inspection and proper arrangement of the garment upon the buck, after which the head is brought down to a pressing position into contact with the garment and held in that position with more or less pressure while it is being reciprocated back and forth by the rotation of the eccentric —28—, during which time steam is applied to the garment through the perforations —26— to supply the necessary moisture, without saturation, which enables the garment to be reshaped and its surface glossed, the backward and forward polishing movement serving to obliterate any imprints of the steam jets which may have been impressed in the surface of the garment, or, what is more to the purpose, serves to prevent the formation of said imprints by the constantly changing positions of the openings or perforations —26— during this pressing operation while the steam is being admitted to the garment through the perforations —26—. Said steam forms a thin elastic cushion over the surface of the garment which greatly assists in the free traversing movement of the perforated plate over said garment surface without liability of wrinkling the garment, it being understood that the traversing movement is comparatively slight, but covers the entire area of both elements in one and the same movement, thereby imparting the desired finish to a correspondingly large area of the garment, which greatly expedites the output by expediting the work and correspondingly reducing the iron marks so common in the use of sad irons and analogous implements.

In some instances, it may be desired to allow the upper pressing element to remain stationary or in its pressing position without the vibratory movement, in which case, the buck —1— with the garment thereon may be reciprocated or caused to traverse the face of the head —2— while the latter is in its pressing position and delivering steam to the garment to impart the desired finish or gloss to the surface thereof. If necessary, both the head and buck may be operated simultaneously to traverse the surfaces of each other by the operation of both of the eccentrics —13— and —28—, one motion being rectilinear and the other gyratory.

It is evident, however, that other means may be provided for producing these movements, and, therefore, I do not wish to limit myself to the construction shown and described, since the essential purpose is to permit the application of steam to a relatively large area of the garment during the pressing operation, and, at the same time, to impart a traversing movement to one or the other of the pressing elements for the pur-

pose of avoiding the production of imprints from the steam jets and also of producing a glossy and smooth finish to the surface of the garment.

5. What I claim is:

1. In a garment pressing machine comprising similar coöoperative pressing elements, one of which is movable toward and from the other, one of said elements having steam exit openings through its presser face, and means for causing one of the elements to traverse the face of the other element with a slight recurrent motion when said elements are in their pressing positions to avoid imprints of the steam jets, and to produce glossy finish to the surface of the garment.
2. A garment pressing machine comprising coöoperative pressing elements of substantially equal area, one of said elements having a perforated press plate provided with a smooth polishing surface, means for causing the last named element to move across the surface of the other element with a recurrent motion while the elements are in their pressing positions, and means for projecting steam through the perforated plate.
3. In a garment pressing machine, a gar-

ment supporting buck, a superposed press head movable toward and from the buck and provided with a perforated press plate having a smooth polishing surface, means for projecting steam through the perforated plate to the garment on the buck, and means for causing one of the pressing elements to move with a recurrent motion across the 30 pressing face of the other element when said elements are in their pressing positions.

4. In a garment pressing machine, two steam heated pressing elements of similar area, and means for causing one of the elements to move with a recurrent motion across the surface of the other element, one of said elements having a perforated press plate provided with a smooth polishing surface, and means for projecting steam 35 through the perforated plate to the garment during the said recurrent motion.

In witness whereof I have hereunto set my hand.

HAROLD CORTLAND SPENCER.
